Primary Examiner — Mark A Goodwin(74) *Attorney, Agent, or Firm* — Birch, Stewart, Kolasch & Birch, LLP(57) **CLAIM**

The ornamental design for a cab for construction machine, as shown and described.

DESCRIPTION

FIG. 1 is a first perspective view of a cab for construction machine showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portion shown by broken lines is for illustrative purposes only and forms no part of the claimed design.
